BUTTON BACKING FOR SNAP FASTENER ELEMENTS

Paul E. Fenton, Thomaston, Conn., assignor to
Scovill Manufacturing Company, Waterbury,
Conn., a corporation of Connecticut

Application June 13, 1938, Serial No. 213,311

4 Claims. (Cl. 24—217)

This invention relates to improvements in fastener installations, comprising a snap fastener socket or stud element, affixed to one of two overlapping portions of sheet material for cooperation with a complementary fastener element, a stud or socket as the case may be, carried by the other of the supporting sheets.

The principal object of the invention is to provide an installation of this character, particularly for application to the upper of the two portions of sheet material, which presents a sufficiently attractive outward appearance to permit its use upon women's dresses or other articles of wearing apparel similarly subject to frequent and continued style changes.

It is another object of the invention to provide such an installation in which a conventional button may be used as a backing member for the snap fastener element, thereby presenting an attractive, but substantially conventional outward appearance, while obtaining all of the advantages of a mechanical snap fastener installation.

The full nature of the invention, along with other objects and various features thereof, will be more apparent from the following description when read in connection with the accompanying drawing, in which:

Figure 1 is a sectional view, taken on the line 1—1 of Fig. 2, of a pair of overlapping sheets having a snap fastener installation thereon in accordance with the present invention.

Fig. 2 is a plan view of the installation shown in section in Fig. 1.

Fig. 3 is a perspective view of the staple used in attaching the socket element of Fig. 1 to its supporting sheet.

Fig. 4 is a plan view of a button having four central thread openings which may be used as a backing for the socket element of Fig. 1 in place of the two-holed button there shown.

Fig. 5 is a perspective view of a staple adapted to be used with the button of Fig. 4 in affixing a fastener member to a supporting sheet in the manner illustrated in Fig. 1; and

Fig. 6 is a perspective view of a fragment of the button of Fig. 4 affixed to a supporting sheet by means of the staple illustrated in Fig. 5.

Referring now to the drawing, I have shown in Fig. 1, a snap fastener assembly comprising a socket element 10 attached to one, 11, of two overlapping sheets of material for cooperation with a stud member 12, carried by the other, 13, of the sheets, and illustrating my invention in one of its preferred forms.

It may be assumed that the two sheets of material represent the overlapping seam portions of a lady's dress or similar style garment. Since the upper of these sheets, 11, is visible at all times the fastener element, in this instance, the socket, should be attached thereto in such a way that no

unsightly mechanical part appears on its upper surface. The installation should contribute to and not detract from the decorative scheme. It is evident the attaching caps of the prior art hardly meet this requirement, nor are they available in a sufficient number of styles and sizes to provide that selection which the style designer requires. In order to meet this requirement, I utilize a button like backing member and a staple, the two serving together as an attaching cap for the fastener element 14. In the completed installation the snap fastener element 10 is firmly affixed to the under side of the sheet 11 for ready and easy cooperation with the complementary stud element, and the button like backing member which appears on the upper side of the sheet may have decorative qualities enhancing the general appearance of the garment. This makes it possible for the dress designer to select from existing stock buttons of the style, color and size which best fit in with his decorative scheme, and to employ them as parts of the fastener attaching means. The installation may thus be given an attractive outward appearance which is substantially identical with that of an ordinary button and buttonhole combination; and the latter effect may be enhanced, if desired, by the application of a small amount of embroidery 37 (Fig. 2) to simulate the ends of a buttonhole.

The installation in Fig. 1 includes a socket constructed in accordance with my Patent No. 2,106,728, comprising a single piece of sheet metal having a central, circular series of resilient fingers 16, each provided at its free front end with an inturned stud engaging lip 17, an anvil portion 18, integrally joining the rear ends of the fingers and flaring forwardly and outwardly therefrom with the outermost portion of its front surface lying in a plane spaced forwardly from the free ends of the fingers, and a marginal retaining ring 19 turned rearwardly and inwardly from the outer extremities of the anvil so as to define an annular entrance slot 20 to the ring from the rear side of the element.

In attaching the just described socket to its supporting sheet, I employ a staple 21 of the type shown in Fig. 3. Thus after assembling the socket and the backing member 14 (the button) on opposite sides of the sheet 11, in back to back relation, with the substantially flat back 22 of the button engaging the front (upper) surface of the sheet and with the rear flange of the retaining ring of the socket engaging the under side of the sheet, I drive the more or less sharply pointed prongs 23 of the staple through the centrally located thread openings 15 of the button, the sheet, the entrance slot 20 of the retaining ring of the fastener element, and against the rear surface of the anvil 18 of the element so as to force the ends of the prongs outwardly and clinch

them within the retaining ring. This operation, of course, is continued until the crown 24 of the staple engages the button and forces it against the sheet.

The button 14 of Figs. 1 and 2, having only two central thread openings, may be replaced by a four-holed one 14a such as is shown in Fig. 4. If so, then all four of its openings 15a should be covered in order that the front surface of the button will present a conventional appearance. This may conveniently be accomplished by the use of a four pronged staple 21a (Figs. 5 and 6) comprising a single piece of sheet metal with an X-shaped crown 24a and four pointed prongs 23a projecting rearwardly from the opposite ends of the crown. The attaching operation, in either event, will be the same as that hereinbefore described.

The illustrated buttons are of the kind which are molded from gaily colored plastic material with their front surfaces embodying ornamental designs. The detail is a matter of style and taste, but in general character the design should include a central recess surrounding the thread openings. The point is well illustrated in Figs. 1 and 4. It will be noted that each design includes an upstanding rim (25 of Fig. 1, 25a of Fig. 4) defining a central recess (26 in the case of Fig. 1, 26a in Fig. 4) within which the thread openings are formed. A design of this character is preferred for it provides a space (the recess 26 or 26a) within which the crown of the staples may lie, protected from injury by contact with outside objects and effectively shielded so that it may not damage such objects by contact with them.

I have shown in Fig. 1, a stud member 12 of the type described in my co-pending application No. 176,189, filed November 24, 1937 (now Patent No. 2,131,347, dated September 27, 1938), comprising a central stud post 29 having a contracted neck 30 for cooperation with the resilient fingers of the socket, and an anvil portion flaring forwardly and outwardly with its margin directed rearwardly and inwardly to define a retaining ring 31. This stud is shown applied to its sheet by means of an attaching cap having an annular flange 32 engaging the under side of the supporting sheet 13 and several prongs 33, extending through the sheet and clinched within the retaining ring 31 of the stud member.

I have illustrated the socket member 10 applied to the outermost sheet 11, and backed by a conventional button. This has been done for illustrative purposes, and nothing more. Although it is usual to affix the socket to the outer of the overlapping sheets, and the stud to the lower one, the positions of these parts may be reversed if desired.

The use of a conventional button as a backing for a snap fastener element greatly enhances the outward appearance of the completed installation as has been said. Thus, the installation retains all of the chic features of a conventional button and button-hole combination while avoiding all of its disadvantages. In addition, the button serves as a very excellent backing for the fastener, making its attachment to the supporting sheet more secure—it tends to prevent the fastener member from being stripped from the sheet. Moreover, the combination provides the garment manufacturer with a tremendously wide selection

of what amount to "attaching caps" for the fastener element, and this without involving any additional expense to any of the various parties concerned. The button manufacturer, for example, need only stock his usual assortment of buttons; the fastener manufacturer, only two or three very simple types of attaching caps along with his usual line of snap fastener elements. If either makes any changes, the former in the matter of size, shape, color or general design of his buttons, the latter in the mechanical construction of his fastener parts, the other need not be affected to any great degree. Thus, each may make constant improvements in his own product without materially interfering with the activities of the other. The garment manufacturer may, of course, take his choice of buttons selecting them from a style and price viewpoint, and combine them with the snap fastener member which best meets his needs.

Since certain changes may be made in the construction in the constituent parts of the assembly and in the arrangement thereof without departing from the teachings of the invention, it is intended that the foregoing shall be construed in a descriptive rather than in a limiting sense.

What I claim is:

1. A snap fastener installation comprising a supporting sheet, a snap fastener element disposed with its rear surface engaging one side of said sheet, a backing member disposed with its rear surface engaging the other side of said sheet, and a staple holding the parts in assembled relation; said backing member being of button-like character and having a plurality of openings therein at spaced points about its center; said fastener element comprising a central part adapted for cooperation with a complementary part of another fastener element, and a marginal retaining ring with a reversely-extending free rear edge lying in spaced relation to the central part defining an annular entrance slot to the ring from the rear side of the element; and said staple comprising a crown engaging the front surface of the button-like backing member between the openings thereof and a plurality of prongs extending from the crown through the openings of the backing member, the supporting sheet, and the entrance slot of the fastener element with their free ends disposed within and held by the retaining ring of the element.

2. A snap fastener installation according to claim 1, further characterized in that said backing member has four openings and in that the staple has four prongs directed rearwardly from the crown through such openings.

3. A snap fastener installation according to claim 1, further characterized in that said button has a central recess in its front face, and in that said thread openings are formed within such recess, whereby the crown of said staple may lie within such recess and be shielded by surrounding portions of said button.

4. A snap fastener installation according to claim 1 characterized in that the central part of said fastener element which is adapted for cooperation with a complementary part of another fastener element is of resilient character defining a socket for cooperation with such complementary part.

PAUL E. FENTON.
